RECEPTACLE

Christian A. Buscham, Newark, N. J., assignor to
 Exotic Vanities, Inc., New York, N. Y., a corporation of New York

Application March 4, 1935, Serial No. 9,149

5 Claims. (Cl. 206—37)

This invention relates generally to improvements in receptacles and more particularly to cigarette and vanity cases and combination cases.

5 An object of this invention is to provide a cigarette and/or vanity case which will be characterized by its efficiency, simplicity and economy of manufacture.

A further object of the present invention is

10 to provide a vanity or cigarette case of novel construction and having an articulated, slideable closure.

A further object is the provision of a case or receptacle adapted for carrying cigarettes or 15 small toilet articles or both, and at the same time possessing all of the advantages of compactness, facility in operation, artistic appeal, convenience, extreme practicability in use and construction, desirable in devices of this class.

20 The present invention utilizes an articulated closure made slideable with respect to the body of the case by cooperation between opposite sides of the closure and continuous channels in side members secured to the case body. The 25 side members are secured to the case body in a novel way, enabling the cover to be positioned during assembly of the device in a simple and inexpensive manner. The articulated closure comprises a plurality of separate strips transversely arranged and means to connect the strips together.

Other objects and features of the invention will be apparent from a consideration of the 30 detailed description taken with the accompanying drawings wherein:

Fig. 1 is a top plan view of a case embodying the invention showing slideable articulated closure in closed position.

Fig. 2 is a side elevational view of Fig. 1.

40 Fig. 3 is a top plan view of a cigarette case embodying the invention showing slideable articulated closure partly moved back, exposing cigarettes.

Fig. 4 is a top plan view of a compact case 45 embodying the invention showing slideable articulated closure partly moved back, exposing the compact.

Fig. 5 is a sectional view through Fig. 1, along lines 5—5.

50 Fig. 6 is an enlarged view of a portion of Fig. 5.

Fig. 7 is a sectional view along lines 7—7 of Fig. 3.

55 Fig. 8 is a sectional view along lines 8—8 of Fig. 4.

Fig. 9 is a perspective view of a casing shell.

Fig. 10 is a perspective view of one form of side element of the casing, forming a guide track.

Fig. 11 is a perspective view of one form of a 5 cap for said side element.

Fig. 12 is a perspective view of a portion of the articulated cover.

Fig. 13 is a sectional view along lines 13—13 of Fig. 1.

10 Fig. 14 is a perspective view of one strip of the slide closure shown in a modified form.

Fig. 15 is a perspective partial view of a few 15 of the strips shown in Fig. 14 as secured to a side piece.

Referring to the drawings, the invention in its preferred form as applied to a cigarette case may consist of a shell or body 21 having a bottom 22, two upturned sides 23, 24 and upturned rounded ends 25, 26. The sides 23, 24 are provided with a series of lugs or tongues 27 preferably stamped out of the sides, with which side elements 28 are secured.

Each side element 28 has a guide track which may be of continuous U section at the edge 25 forming a continuous or endless channel 41, and may have a depressed central portion forming pocket 42. The wall 29 of pocket 42 is provided with perforations or slots 30 through which lugs or tongues 27 pass, the latter being bent over 30 for locking the side element 28 to shell 21. When the elements 28 are secured to body sides 23, 24, the peripheral guide tracks 41 extend thereabove, and beyond ends 25, 26 and bottom 22, as clearly shown in the drawings.

35 As an example of flexible closure employed, the drawings show an articulated slide closure C which may be made in various ways. One construction is brought about by cementing a piece of cellulosic or other suitable material 31 to a 40 flexible binder 32 made of fabric or other suitable material, and then slitting the cellulosic material down to the binder 32 as shown at 33, but of course not cutting the binder. This makes a dust-proof cover.

45 Both ends of the sliding articulated shutter or cover C may be provided with reinforcing metal strips 34 clamped to the two outermost cover strips. These metal strips 34 are cut back at 50 35 so as to stop outside of the guide track or channel 41. This cutting back of strips 34 form guiding tongues 34' in the rail or channel 41.

55 The closure may be made up of elements associated with the strips to flexibly unite the latter. For example the shutter or closure may be made

up of a plurality of metal strips 36 which may have thin ends 37, 38 bent over a flexible element 39 made of spring steel. Any suitable cord, wire or chain may be substituted for element 39.

5 Portion 40 will in this case ride in groove or track 41 of side member 28.

After the various parts are assembled, the pocket 42 of side member 28 is closed by a cap 43, preferably of U-section, having shallow 10 tongues 44 at both ends, which projecting tongues engage slots 45 of the side member 28. The cap is thereby snapped into place and securely held there, but can also be again removed for repair purposes.

15 This invention may also be applied to a vanity case. As illustrated in Fig. 8, a separate vanity case insert V may be located within the space formed by the side and end walls of the shell. Compartment A may be used for rouge and lip- 20 stick; compartment B for face powder; or compartment A for face powder and compartment B for cigarettes. Both compartments are closed by auxiliary covers 46 and 47, respectively, which may be hinged as shown at 48. It is understood 25 that the insert may comprise a single compartment. The removable insert V has downwardly curved ends 49, 50, which abut against the arcuate ends 25, 26 of case shell 21 when snapped into position.

30 In the accompanying drawings I have illustrated the invention embodied in its practical commercial forms but as these illustrations are primarily for purposes of disclosure it will be understood that the invention is not limited to 35 these particular forms of structure and that it may be modified in many respects without departure from the true spirit and scope of the invention as herein defined and claimed.

I wish it further understood that the terms 40 which I have employed herein are used in a descriptive rather than in a limiting sense, except however for limitations that may be imposed by the state of the prior art.

Having thus described my invention what I 45 claim as new and desire to secure by Letters Patent, is:

1. A cigarette or vanity case of the character described, comprising a shell having side walls, said walls having lugs, a pair of side pieces, 50 each of said side pieces having an inwardly depressed central portion and perforations in said portion in register with said lugs, said lugs projecting through said perforations and being bent over whereby said side pieces are secured 55 to said walls, each of said side pieces having a continuous channel surrounding the wall to which it is secured, and an articulated closure in slidable engagement with said channels, said

closure comprising a plurality of strips of material transversely arranged and means for connecting said strips together.

2. A cigarette or vanity case of the character described, comprising a shell having side walls, 5 said walls having lugs, a pair of side pieces, each of said side pieces having an inwardly depressed central portion and perforations in said portion in register with said lugs, said lugs projecting through said perforations and being bent over whereby said side pieces are secured to said walls, a cover fitting said central portion for concealing said lugs, each of said side pieces having a continuous guide surrounding the wall to which it is secured, and an articulated cover 10 in slidable engagement with said guides, said cover comprising a plurality of strips of material transversely arranged and means for connecting said strips together.

3. A cigarette or vanity case of the character 15 described, comprising a shell having side walls, said walls having lugs, a pair of side pieces, each of said side pieces having an inwardly depressed central portion and perforations in said portion in register with said lugs, said lugs projecting through said perforations and being bent over whereby said side pieces are secured to said walls, a cover fitting said central portion for concealing said lugs, said cover having projections and said side pieces having openings in 20 register with said projections, each of said side pieces having a continuous guide surrounding the wall to which it is secured, and an articulated cover in slidable engagement with said guides, said cover comprising a plurality of strips 25 of material transversely arranged and means for connecting said strips together.

4. A case of the character described comprising a shell having side walls, a pair of side pieces having inwardly depressed central portions secured to the side walls, each of said side pieces having a continuous channel surrounding the wall to which it is secured, and a flexible closure having its side edges slidable 30 in said channels.

5. A case of the character described comprising a shell having side walls, a pair of side pieces, each of said side pieces having an inwardly depressed central portion, means for securing said depressed central portions to the 35 side walls, each of said side pieces having a continuous channel surrounding the wall to which it is secured, and an articulated closure having its side edges slidable in said channels, said closure comprising a plurality of strips of material transversely arranged and means for connecting said strips together.

CHRISTIAN A. BUSCHAM.
